CLAIM

We claim the ornamental design for workstation, as shown and described.

DESCRIPTION

FIG. 1 is a right side elevation view of a workstation.

FIG. 2 is a left side elevation view of the workstation of FIG. 1.

FIG. 3 is a front elevation view of the workstation of FIG. 1.

FIG. 4 is a back elevation view of the workstation of FIG. 1.

FIG. 5 is a top plan view of the workstation of FIG. 1; and,

FIG. 6 is a bottom plan view of the workstation of FIG. 1.

The broken lines are provided for illustrative purposes only and form no part of the claimed design.
